UNITED STATES PATENT OFFICE.

ELBERT A. CORBIN, JR., OF PHILADELPHIA, PENNSYLVANIA.

DOUBLE-DECK BUS.

Application filed March 3, 1923. Serial No. 622,497.

- In the conventional double deck motor coach of the character commonly in vogue, there has heretofore been employed an unsheltered outside rear stairway for permitting the ascent of the passengers to the upper deck, which outside rear stairway has always been so designed that it took up a great deal of unnecessary room, and in addition being always open to storms and the effects of inclement weather, the steps thereof in bad weather were always open to the effects thereof and quickly became wet or slippery or coated with ice and were very unsafe. This condition has always had a tendency to intimidate passengers from venturing aloft and has tended to a loss of revenue from the reluctance of passengers to take the risk incurred in clambering to the upper deck, particularly if the vehicle was in motion.
- For the purpose of obviating the foregoing objectionable condition, I have devised a novel construction and collocation of enclosed, inside front stairway for a motor coach which takes up very little room, is weather proof, and being wholly within the vehicle body, gives the ascending passenger a sense of security and safety and enables the transportation company to sell the upper deck seats more readily, and thus utilize the entire seating or carrying capacity of the motor coach.
- My novel stairway is so designed and collocated within the front of the vehicle that the user thereof upon entering the front of the coach walks entirely across the front vestibule beyond the center aisle line before reaching the first or lower treads, so that he is entirely within the vehicle before beginning his ascent, and in addition by my novel construction, I bring the main entrance to the coach on the outer right hand side and the driver is enabled to approach closely to the curb, loading on passengers with ease, and he is further enabled to see that all passengers are safely on or off the coach before he starts the vehicle again.
- My invention further consists in providing a front overhang for the upper deck in advance of the exit at the top of the inside front stairway, whereby not only is the traffic divided in two ways, but twelve or more
- seats are provided in the front of the stairway on the upper deck, thereby greatly increasing not only the accessibility to the upper deck, but also the capacity thereof.
- It further consists of a novel construction of an L-shaped door, coacting with the head opening of the roof of the upper deck, which enables the passengers readily to complete their ascent of the last three or four steps to the upper deck.
- To the above ends my invention consists of a spiral stairway common to the upper and lower decks, located in the front of the coach opposite to the passenger entrance to the lower deck, so that the front end of the aisle of the lower deck intervenes between said entrance and the lower treads, the latter being spaced away from the front end of the coach, so as to provide ample room for the driver and conductor at the front, while the upper treads terminate at the upper deck a little distance to the rear of the front of said upper deck, so as to divide the upper deck traffic in two directions.
- It further consists of the combination of a stairway having the characteristics aforesaid with a vertical hand rail which isolates the driver from the passengers and conductor.
- It further consists of the novel combination of a stairway and hand rail of the character aforesaid, with an L-shaped door for the upper deck collocated in a novel manner with respect to said stairway and its adjuncts.
- It further consists of a novel construction of an inside spiral front stairway common to the upper and lower decks and a vertical hand rail on the lower deck spaced away from the stair treads, so as to isolate the driver and afford a maximum space for the ascending and descending passengers, and the standers to move about in.
- For the purpose of illustrating my invention, I have shown in the accompanying drawings forms thereof which are at present preferred by me, since they will give in practice satisfactory and reliable results, although it is to be understood that the various instrumentalities of which my invention consists can be variously arranged and organized and that my invention is not limited to

the precise arrangement and organization of these instrumentalities as herein shown and described.

Figure 1 represents a side elevation of a motor coach embodying my invention.

Figure 2 represents a horizontal section on line 2—2 Figure 1.

Figure 3 represents a horizontal section on line 3—3, Figure 1.

10 Figure 4 represents a vertical section on line 4—4 Figure 2.

Figure 5 represents a vertical section on line 5—5 Figure 3.

15 Figure 6 represents a perspective view of the L-shaped door employed on the upper deck in detached position.

Similar numerals of reference indicate corresponding parts in the figures. Referring to the drawings.

20 1 designates my novel construction of motor coach, the same comprising the lower deck 2 and the upper deck 3. At the front of the lower deck I locate a post or upright 4, on each side of which are the front folding doors 5 and 6, which are actuated by any suitable mechanism and are adapted to fold inwardly as seen in Figure 3. The passenger on entering the front of the lower deck steps on the step 7 and walks across the front end 25 of the centre aisle 8 to the lower treads 9, 10, 11 and so on of the spiral stairway 12, having the center stringer 13 within which is the vertical post 14 and the outer stringer 15. The hand rail 16, in advance of the 30 stairway, and whose rear portion may be connected to the stairway, segregates the motorman's seat 17 from interference by the ascending, descending or standing passengers, and as the latter complete their ascent 35 to the upper deck 3, they step out through the opening 21 upon the floor 18 into the center aisle 19 of the upper deck and can then occupy the seats 20.

40 The opening 21 is closed by a sliding L-shaped door 22 composed of the upright member 23, and the lateral member or top 24, whose outer end slides upon the guide 26 which may be below the roof, as shown, or above the roof, the lower edge of the door 45 sliding in the ways or guide 25. The roof of the upper deck has a central longitudinal opening as indicated at 27, (Fig. 5) and the portion of the roof vertically above the uppermost treads 28 of the spiral stairway 50 has the head opening 29 which permits the passengers to walk up the upper treads 28 and step out upon the floor 18 of the upper deck without interference and when the door 22 is closed or slid to the left of the position 55 seen in Figure 4, said opening 29 is closed by the top portion 24 of the door. It will be noted that the front upper deck is provided with a forward overhang 30 in advance of the upper end of the spiral stairway 12, which projects out over the hood 31

of the motor and in this upper deck space in advance of the stairway I am enabled to seat twelve people as will be understood from the right hand end of Figure 2, thereby greatly augmenting the upper deck 70 seating capacity over prior constructions, and in addition by my novel positioning of the upper stairway, I divide the upper deck traffic in two directions. The position of the lower outer stringer 15 of the stairway 75 and the railing 16 further serves to isolate the driver or motorman, keeping him out of the range of the passengers so that he is rendered less liable to converse with them while on duty. The position and collocation 80 of my novel stairway with respect to the front entrance also provide an enlarged front vestibule in the forward end of the lower deck at the point 31*, as will be understood from Figure 3 which gives room for the conductor to have a seat without blocking up the aisle, and a front standing space is thus provided for twelve passengers to stand, while the coach is starting up, thus enabling the conductor to collect fares more 85 readily.

In order to obtain the requisite head room in the front lower deck, I eliminate entirely the sills heretofore commonly employed on which the body rests and substitute therefor a metal plate 32 of aluminum or the like of sufficient thickness to hold the coach sides 33 together, and employ outriggers 34 which are riveted to the longitudinally extending frame channels 35 of the chassis, as will be understood from Figure 5 by which expedients I gain three inches vertically between the flooring of the lower and upper decks, which gives the requisite and necessary head room on the lower deck. I am 90 also enabled by this lowering of the plate or floor 32 to employ a short step 7 which is rigid and stationary, and above which are fitted the lower ends of the folding doors 5 and 6, which are hinged to the rear and front posts 36 and 37, respectively, so that when they are open or folded inwardly as seen in Figure 3, a wide opening is provided for the ingress and egress of the passengers.

95 Only the lower deck 2 is heated, since the upper deck 3 is open above the aisle, but the seated passengers on the upper deck are adequately protected from inclement weather by the overhanging roof sections 35, as will be evident from Figure 5.

100 It will be apparent from the foregoing that by reason of the forward overhang 30 seen in Figures 1 and 2, I am enabled to greatly increase the seating capacity of the upper deck and by positioning the stairway at the point indicated, I am enabled to divide the upper deck traffic in two directions 105 so that a considerable portion of the same can occupy the seats in the front overhang 30 and by the provision of the L-shaped 110

door 22, I am enabled in inclement weather to protect passengers on the lower deck from the snow, sleet or rain which might otherwise have ingress to the lower deck and to 5 the treads of the spiral stairway. By this construction the treads of the stairway are obviously protected from becoming slippery or coated with ice, snow or sleet, which is a very desirable feature in the practical use of 10 devices of this character. The provision of the enlarged front vestibule 31 $\frac{1}{2}$, which I obtain by reason of my novel positioning of the stairway, provides an enlarged area for standers on the lower deck and in addition 15 affords ample room for the conductor to move about in while collecting fares.

It will also be apparent that by reason of 20 my novel construction, the driver and conductor can at all times readily carefully watch the ingress and egress of the passengers and the driver is enabled to approach 25 closely to the curb so as to leave on passengers with ease and between the driver and conductor, both of whom are stationed in proximity to the front entrance, it can be readily ascertained that all passengers are 30 on safely or off the coach before the driver starts the vehicle again.

It will now be apparent that I have devised 35 a novel and useful inside front stairway and door for double deck motor coaches which embodies the features of advantage enumerated as desirable in the statement of the invention and the above description, and 40 while I have, in the present instance, shown and described preferred embodiments thereof which will give in practice satisfactory and reliable results, it is to be understood that the same are susceptible of modification in various particulars without departing 45 from the spirit or scope of the invention or sacrificing any of its advantages.

Having thus described my invention what 50 I claim as new and desire to secure by Letters Patent, is:—

1. In a motor coach, an upper and lower deck, a front right hand side entrance to 55 said lower deck, a driver's compartment and seat at the front left hand side of said lower deck, partitioning means between said entrance and driver's compartment for isolating the driver, a front inside stairway common to said decks, the front of the central aisle of the lower deck intervening between 60 said front entrance and the lower treads of said stairway, the latter being positioned in the rear of said driver's compartment, and the exit from the top of said stairway to the upper deck, being spaced to the rear of the front of said upper deck to divide the traffic thereon in two directions in combination with a head opening in the roof of said upper deck in vertical alignment with the top of said stairway, and a row of transverse 65 seats on each side of said upper deck, the for-

ward portion of said upper transverse seats being in advance of the upper exit of said stairway.

2. In a motor coach, an upper and lower deck, a front entrance to said lower deck, a 70 front inside stairway common to said decks, the front of the aisle of said lower deck intervening between said entrance and the lower treads of said stairway, and the exit from the top of said stairway to the upper deck being spaced to the rear of the front of said upper deck to divide the traffic thereon in two directions, in combination with a head opening in the roof of said upper deck in vertical alignment with the top of said stairway. 75

3. In a motor coach, an upper and lower deck, a front entrance to said lower deck, a 80 front inside stairway common to said decks, the front of the aisle of said lower deck intervening between said entrance and the lower treads of said stairway, and the exit from the top of said stairway to the upper deck being spaced to the rear of the front of said upper deck to divide the traffic thereon in two directions, in combination with a head opening in the roof of said upper deck in vertical alignment with the top of said stairway, and a door on said upper deck for 85 closing said head opening. 90

4. In a motor coach, an upper and lower deck, a front entrance to said lower deck, a 95 front inside stairway common to said decks, the front of the aisle of said lower deck intervening between said front entrance and the lower treads of said stairway, the exit from the top of said stairway to the upper deck being spaced to the rear of the front of said upper deck so as to divide the upper deck traffic in two directions, a row of seats on each side 100 of said upper deck, a roof on said upper deck open at its longitudinal central portion but having an overhang projecting over said rows of seats, a head opening in said roof in vertical alignment with the upper end of 105 said stairway, and an angularly shaped sliding door for said upper deck having an upper lateral extension adapted to close said head opening. 110

5. In a motor coach, an upper and lower deck, a front right hand side entrance to said lower deck, a driver's compartment and seat at the front left hand side of said lower deck, partitioning means between said entrance and driver's compartment for isolating the 115 driver, a front inside stairway common to said decks, the front of the central aisle of the lower deck intervening between said front entrance and the lower treads of said stairway, the latter being positioned in the rear of said driver's compartment, and the exit from the top of said stairway to the upper deck being spaced to the rear of the front of said upper deck to divide the traffic thereon in two directions in combination with a head 120 opening in the roof of said upper deck in vertical alignment with the top of said stairway, and an angularly shaped sliding door for said upper deck having an upper lateral extension adapted to close said head opening. 125

6. In a motor coach, an upper and lower deck, a front right hand side entrance to said lower deck, a driver's compartment and seat at the front left hand side of said lower deck, partitioning means between said entrance and driver's compartment for isolating the driver, a front inside stairway common to said decks, the front of the central aisle of the lower deck intervening between said front entrance and the lower treads of said stairway, the latter being positioned in the rear of said driver's compartment, and the exit from the top of said stairway to the upper deck being spaced to the rear of the front of said upper deck to divide the traffic thereon in two directions in combination with a head 130 opening in the roof of said upper deck in vertical alignment with the top of said stairway, and an angularly shaped sliding door for said upper deck having an upper lateral extension adapted to close said head opening.

- opening in the roof of said upper deck in vertical alignment with the top of said stairway, a row of transverse seats on each side of said upper deck, the forward portion of said upper transverse seats being in advance of the upper exit of said stairway, and a roof for said upper deck having a head opening therein above the upper exit of said stairway.
- 10 6. In a motor coach, an upper and lower deck, a front right hand side entrance to said lower deck, a driver's compartment and seat at the front left hand side of said lower deck, partitioning means between said entrance and driver's compartment for isolating the driver, a front inside stairway common to said decks, the front of the central aisle of the lower deck intervening between said front entrance and the lower treads of said stairway, the latter being positioned in the rear of said driver's compartment, and the exit from the top of said stairway to the upper deck being spaced to the rear of the front of said upper deck to divide the traffic thereon in two directions in combination with a head opening in the roof of said upper deck in vertical alignment with the top of said stairway, a row of transverse seats on each side of said upper deck, the forward portion of said upper transverse seats being in advance of the upper exit of said stairway, and a roof for said upper deck having a head opening therein above the upper exit of said stairway, said upper deck roof being open throughout its longitudinal central portion and having inwardly extending lateral overhangs projecting over said upper rows of transverse seats.

ELBERT A. CORBIN, JR.
